(57) **ABSTRACT**

A new and distinct cultivar of *Anthurium* plant named 'AN2824663', characterized by its upright to outwardly arching and uniform plant habit; freely clumping growth habit; bushy and dense plants; narrowly cordate dark green-colored leaves; freely flowering habit; inflorescences that are positioned within to slightly above the foliar plane on strong and erect scapes; large broadly cordate white-colored spathes and pale yellow-colored spadices; and durable spathes that impart good inflorescence longevity.

1

Botanical designation: *Anthurium andeanum*.
Cultivar denomination: 'AN2824663'.

STATEMENT REGARDING PRIOR
DISCLOSURES BY INVENTOR AND
APPLICANT/ASSIGNEE

An European Community Plant Breeder's Rights application for the instant plant was filed by the Applicant/Assignee of the instant application, Anthura B.V. of Bleiswijk, The Netherlands on Nov. 22, 2022, application number 2022/2631. Foreign priority is not claimed to this application.

The Inventor and Applicant/Assignee assert that no sales, offers for sale or public distribution of the instant plant occurred more than one year prior to the effective filing date of this application.

Any information about the claimed plant would have been obtained from a direct or indirect disclosure from the Inventor and/or Applicant/Assignee. Inventor and Applicant/Assignee claim a prior art exception under 35 U.S.C. 102(b)(1) for disclosures and/or sales prior to the filing date but less than one year prior to the effective filing date.

BACKGROUND OF THE INVENTION

The present invention relates to a new and distinct cultivar of *Anthurium* plant, botanically known as *Anthurium andeanum* and hereinafter referred to by the name 'AN2824663'.

The new *Anthurium* plant is a product of a controlled breeding program conducted by the Inventor in Bleiswijk, The Netherlands. The objective of the breeding program is to create new freely-clumping *Anthurium* plants with attractive white-colored, durable and glossy spathes.

The new *Anthurium* plant originated from a cross-pollination made by the Inventor in June 2013 in Bleiswijk, The Netherlands of a proprietary selection of *Anthurium andrea-*

num identified as code number 05-008641-0001, not patented, as the female, or seed, parent with *Anthurium andeanum* 'Anthewuch', disclosed in U.S. Plant Pat. No. 28,458, as the male, or pollen, parent. The new *Anthurium* was discovered and selected by the Inventor as a single flowering plant within the progeny of the stated cross-pollination in a controlled greenhouse environment in Bleiswijk, The Netherlands in May 2015.

Asexual reproduction of the new *Anthurium* plant by in vitro meristem propagation in a controlled environment in Bleiswijk, The Netherlands since June 2015 has shown that the unique features of this new *Anthurium* are stable and reproduced true to type in successive generations of asexual reproduction.

SUMMARY OF THE INVENTION

Plants of the new *Anthurium* have not been observed under all possible combinations of environmental conditions and cultural practices. The phenotype may vary somewhat with variations in environment conditions such as temperature and light intensity, without, however, any variance in genotype.

The following traits have been repeatedly observed and are determined to be the unique characteristics of 'AN2824663'. These characteristics in combination distinguish 'AN2824663' as a new and distinct *Anthurium* plant:

1. Upright to outwardly arching and uniform plant habit.
2. Freely clumping growth habit; bushy and dense plants.
3. Narrowly cordate dark green-colored leaves.
4. Freely flowering habit.
5. Inflorescences that are positioned within to slightly above the foliar plane on strong and erect scapes.
6. Large broadly cordate white-colored spathes and pale yellow-colored spadices.
7. Durable spathes that impart good inflorescence longevity.

Plants of the new *Anthurium* differ primarily from plants of the female parent selection in the following characteristics:

1. Spathes of plants of the new *Anthurium* are not as rugose as spathes of plants of the female parent selection.
2. Spadices of plants of the new *Anthurium* are not as tapering as spadices of plants of the female parent selection.
3. Spadices of plants of the new *Anthurium* are not as straight as spadices of plants of the female parent selection.

Plants of the new *Anthurium* differ primarily from plants of the male parent, 'Anthewuch', in the following characteristics:

1. Spathes of plants of the new *Anthurium* are broadly cordate in shape whereas spathes of plants of 'Anthewuch' are orbicular cordate in shape.
2. Spathes of plants of the new *Anthurium* are white in color whereas spathes of plants of 'Anthewuch' are bright pinkish red in color.

Plants of the new *Anthurium* can also be compared to plants of *Anthurium andeanum* 'Anthroxol', disclosed in U.S. Plant Pat. No. 32,777. In side-by-side comparisons, plants of the new *Anthurium* differ primarily from plants of 'Anthroxol' in the following characteristics:

1. Spathes of plants of the new *Anthurium* are positioned lower in relation to the foliar plane than spathes of plants of 'Anthroxol'.
2. Spathes of plants of the new *Anthurium* are broadly cordate in shape whereas spathes of plants of 'Anthroxol' are orbicular cordate in shape.
3. Spathes of plants of the new *Anthurium* are larger than spathes of plants of 'Anthroxol'.
4. Spadices of plants of the new *Anthurium* are not as tapering as spadices of plants of 'Anthroxol'.

BRIEF DESCRIPTION OF THE PHOTOGRAPHS

The accompanying photographs illustrate the overall appearance of the new *Anthurium*. The photographs show the colors as true as it is reasonably possible to obtain in colored reproductions of this type. Colors in the photographs may differ slightly from the color values cited in the detailed botanical description which accurately describe the colors of the new *Anthurium*.

The photograph on the first sheet (FIG. 1) is a side perspective view of a typical plant of 'AN2824663' grown in a container.

The photograph on the second sheet (FIG. 2) is a close-up view of typical inflorescences of 'AN2824663'.

DETAILED BOTANICAL DESCRIPTION

The aforementioned photographs and following observations and measurements describe plants grown in 14-cm containers in Bleiswijk, The Netherlands during the late autumn in a glass-covered greenhouse. Plants were grown under conditions and practices which approximate those generally used in commercial *Anthurium* production. During the production of the plants, day and night temperatures ranged from about 19° C. to 22.5° C. and light levels ranged from 100 µmol to 200 µmol. Plants were eleven months old when the photographs and the detailed description were taken. In the following description, color references are

made to The Royal Horticultural Society Colour Chart, 2015 Edition, except where general terms of ordinary dictionary significance are used.

Botanical classification: *Anthurium andeanum* 'AN2824663'.

Parentage:

Female, or seed, parent.—Proprietary selection of *Anthurium andeanum* identified as code number 05-008641-0001, not patented.

Male, or pollen, parent.—*Anthurium andeanum* 'Anthewuch', disclosed in U.S. Plant Pat. No. 28,458.

Propagation:

Type.—By in vitro meristem propagation.

Time to initiate roots, summer and winter.—About two weeks at temperatures about 19° C. to 22.5° C.

Time to produce a rooted young plant, summer and winter.—About six to eight weeks at temperatures about 19° C. to 22.5° C.

Root description.—Medium in thickness, fibrous; typically creamy white in color, actual color of the roots is dependent on substrate composition, water quality, fertilizer type and formulation, substrate temperature and physiological age of roots.

Rooting habit.—Freely branching, medium density.

Plant description:

Plant shape.—Upright to outwardly spreading and uniform plant habit; overall shape, broadly obovate to broadly elliptic.

Growth habit.—Freely clumping habit with about five clumps per plant imparting a bushy and dense appearance; moderately vigorous growth habit and moderate growth rate.

Plant height, from soil level to top of leaf plane.—About 33.2 cm.

Plant height, from soil level to top of inflorescences.—About 37.7 cm.

Plant diameter or spread.—About 40.9 cm.

Leaf description:

Arrangement.—Alternate; simple; about five leaves per clump.

Length.—About 21.1 cm.

Width.—About 12.8 cm.

Shape.—Narrowly cordate.

Apex.—Apiculate with mucronate tip.

Base.—Cordate.

Margin.—Entire; slightly to moderately and coarsely undulate.

Texture and luster, upper and lower surfaces.—Smooth, glabrous; moderately leathery; glossy.

Venation pattern.—Pinnate.

Color.—Developing leaves, upper surface: Slightly darker than 143A. Developing leaves, lower surface: Close to a blend of 144A and 146B. Fully expanded leaves, upper surface: Darker than a blend of NN137A and 139A; venation, close to a blend of 143B and 144A. Fully expanded leaves, lower surface: Close to a blend of 144A and 146B; venation, close to N144A.

Petioles.—Length: About 21.2 cm. Diameter: Distally, about 4 mm; proximally, about 6 mm. Strength: Strong. Texture and luster, upper and lower surfaces: Smooth, glabrous; slightly glossy. Color, upper surface: Close to 144A to slightly darker than 144A. Color, lower surface: Close to 144A. Geniculum

length: About 2.1 cm. Geniculum diameter: About 5 mm. Geniculum texture and luster, upper and lower surfaces: Smooth, glabrous; slightly glossy. Geniculum color, upper surface: Close to 144A. Geniculum color, lower surface: Close to a blend of 144B and 144C. Wing length: About 2.8 cm. Wing diameter: About 6 mm. Wing color: Close to 144A; towards the margins, close to 144B.

Inflorescence description:

Inflorescence arrangement and flowering habit.—¹⁰ Spathes with spadices held within and slightly above the foliar plane on strong and erect scapes; flowering structures arise from leaf axils; freely and continuous flowering year-round in controlled temperature greenhouses in The Netherlands; typically about six ¹⁵ developing and developed inflorescences per plant at one time; inflorescence development commences about 2.5 to 3.5 months after planting.

Inflorescence longevity.—Spathes maintain good substance for about two months on the plant; inflorescences persistent. ²⁰

Fragrance.—None detected.

Spathes.—Length: About 11.1 cm. Width: About 13.4 cm. Shape: Broadly cordate; moderately concave. Apex: Broadly apiculate to abruptly acute with a mucronate tip. Base: Cordate. Margin: Entire; slightly and coarsely undulate. Aspect: At about 97.5° from the peduncle axis. Texture and luster, upper and lower surfaces: Smooth, glabrous; moderately leathery; glossy. Color: When developing, front surface: Close to NN155D with tip, close to 155C. When developing, rear surface: Close to 155C with tip, close to 150C; towards the base, close to 157D. Fully developed, front surface: Close to 155B with tip, close to 145C; venation, close to 155B; with ³⁰ subsequent development, color becoming closer to

5

157B and towards the base, closer to 138B with venation, closer to 143B. Fully developed, rear surface: Close to 155C with tip, close to 145B; venation, close to 144B; with subsequent development, color becoming closer to 145A to 145D and towards the base, closer to 144B and 144C with venation, closer to 143A and 143B.

Spadices.—Length: About 5.5 cm. Diameter: About 1 cm. Shape: Columnar, slightly tapering towards the apex; apex, obtuse; base, obtuse; in cross-section, rounded. Aspect: About 55° from the spathe axis and about 55° from the peduncle axis; slightly curved downward. Color: Immature: Close to 10C and distally, close to 145B. Mature: Close to 11C and distally, close to 11A. Flowers: Type: Hermaphroditic. Quantity per spadix: Numerous, about 240. Height: Less than 0.5 mm. Diameter: About 2.5 mm. Shape: Roughly square. Anther color: Close to 11C. Pollen amount: Scarce to medium. Pollen color: Close to 155D. Stigma color: Close to 11D.

Scape.—Length: About 24.8 cm. Diameter: About 4 mm. Strength: Strong. Aspect: About 20° from vertical. Color: Close to 144A.

Seed and fruit.—To date, seed and fruit development has not been observed on plants of the new *Anthurium*.

Pathogen & pest resistance: To date, plants of the new *Anthurium* have not been observed to be resistant to pathogens or pests common to *Anthurium* plants.

Temperature tolerance: Plants of the new *Anthurium* have been observed to be tolerant to high temperatures about 30° C. and to be hardy to USDA Hardiness Zone 10.

It is claimed:

1. A new and distinct *Anthurium* plant named 'AN2824663' as illustrated and described.
